MOLDED HAND HELD PADDLE FOR
BATTING FOAM BALLS

Charles F. Foley, Minnetonka, Minn.

Filed Mar. 21, 1973, Ser No. 343,369

Term of patent 14 years

Int. Cl. D21—02

U.S. Cl. D34—5 ST

FIG. 1 is a top plan view of a molded hand held paddle for batting foam balls embodying my new design;

FIG. 2 is a left edge view thereof;

FIG. 3 is a right edge view thereof;

FIG. 4 is a side view thereof, the opposite side being substantially a mirror image of the side shown; and

FIG. 5 is a sectional view thereof taken on line 5—5 in FIG. 1.

I claim:

The design for a molded hand held paddle for batting foam balls, substantially as shown and described.
